UNITED STATES PATENT OFFICE.

DANIEL BEST, OF SAN LEANDRO, CALIFORNIA.

GAS-ENGINE MOTOR FOR CARS.

SPECIFICATION forming part of Letters Patent No. 496,717, dated May 2, 1893.

Application filed September 9, 1892, Serial No. 445,453. (No model.)

To all whom it may concern:

Be it known that I, DANIEL BEST, a citizen of the United States, residing at San Leandro, county of Alameda, State of California, have 5 invented an Improvement in Gas-Engine Motors; and I hereby declare the following to be a full, clear, and exact description of the same.

My invention relates to an improved gas engine and the transmission of power from it 10 to propel a car.

It consists in certain details of construction which will be more fully explained by reference to the accompanying drawings, in which—

15 Figure 1 is a plan view. Fig. 2 shows a modification. Fig. 3 is an elevation of the same. Fig. 4 is a face view of the clutch mechanism. Fig. 5 is a vertical section taken in the plane of one of the wheel axles showing the clutch mechanism.

The object of my present invention is to provide a simple, compact, and effective mechanism by which the power of a pair of gas engines may be applied simultaneously to either 25 one of the wheel axles of a car, and a means by which the application of the power to one pair of the car wheels will drive the car in one direction and its application to the other pair will drive it in the opposite direction.

30 A is the engine bed having legs B at opposite ends by which it is supported upon the floor of a car to which power is to be applied. At each end of this bed is cast the circular head C and to these heads the cylinders D are 35 are bolted, the cylinders being also bolted to supported upon a shelf E which is formed at each end above the legs and behind the circular head C. These heads are mounted upon the bed so that vertical planes through

40 their axes will pass upon opposite sides of a central line and sufficiently far apart so that the connecting rods F will connect centrally with the pistons in their respective cylinders, and with the cranks G which are formed upon 45 the crank shaft H. This arrangement is accomplished by the peculiar construction of the bed-piece A which is formed with offsets or curves upon opposite sides as plainly shown in the plan view by which the cylinders are 50 disposed with relation to each other as above described.

Between the ends C is formed a trough-

shaped depression I which gradually deepens from each end toward the center where it is sufficiently deep, as shown at I' to allow the 55 cranks G to rotate freely without contact with the frame. A strengthening rib J having essentially the same curvature with the trough I I' extends between the legs B projecting from the bottom of the trough, and forms a 60 rigid support for the whole frame-work.

The crank shaft H is journaled across the center of the frame and carries upon the outside of the frame a pinion K. This pinion meshes with one of the gears L, and this in 65 turn meshes with the other gear L, and from these the mechanism for actuating the valves is driven, this not being shown as it forms no part of my present invention.

M M are the governors of the two engines 70 which are driven by belts N passing over pulleys O upon the horizontal shafts extending outwardly from and meshing with the gears upon the vertical governor spindle. The belts from the pulleys O pass around central 75 pulleys P upon the engine shaft and thus receive their power. Upon the opposite end of the crank shaft and outside the frame, is fixed a sprocket wheel Q.

The car axle R has upon it a sprocket wheel 80 S suitably proportioned to the wheel Q to produce the desired rate of speed. In the present case I have shown these sprockets approximately in the proportion of nine to sixteen. A chain T extends between these sprockets, and by these means, while the engine is 85 running, power is transmitted to drive the car in one direction.

U is a gear wheel fixed upon the shaft H near the sprocket Q, and made of slightly 90 larger diameter to prevent the chain of the sprocket wheel riding upon it in case of accident. This gear wheel meshes with a second gear wheel V which is mounted to rotate upon a shaft extending outward from the side of 95 the frame, and journaled as shown. Upon the same shaft is mounted another sprocket wheel X and upon the other axle R' of the car is fixed a sprocket wheel S', around which, and the sprocket wheel X passes the driving 100 chain T'. It will be seen that by reason of the gears U and V, the sprocket wheel X will be driven in the opposite direction from the sprocket wheel Q, and, consequently, when

the power of the engine is transmitted through the chain T' to the sprocket wheel S' the pair of car wheels to which the power is then applied will be rotated in the opposite direction 5 from the wheels driven directly from the sprocket Q , and thus the car can be driven in the opposite direction. It will be manifest that power cannot be applied to both these pairs of car wheels at the same time, and in 10 order to release one pair of wheels while the other is at work, I employ any suitable clutch mechanism by which power can be applied to either set, and thrown off from the other.

Fig. 1 shows the clutch mechanisms applied 15 to the crank shaft and the counter shaft, and Figs. 2 and 3 show the clutches applied upon the car axles.

As shown in Figs. 2 and 3, the sprocket wheel S or S' is mounted upon a sleeve a , preferably made in halves, and bolted over the axle of the car so that it can be easily removed at any time. The hub of the sprocket wheel is also made in the same manner, so that the sprocket wheel is removably secured 25 upon this sleeve. Upon the sleeve a is cast or otherwise secured a disk b having projecting flanges c concentric with the axle, and forming with the disk b a shallow cup fixed to the sleeve a . It will be manifest that as 30 this sleeve a turns loosely upon the axle, the power of the engine will simply rotate the sprockets S and S' upon their respective axles without transmitting any power to either. In order to connect either of these sprocket 35 wheels with its axle, I employ a clutch mechanism fixed to the axle and adapted to clamp against the rotating disk flanges c . In the present case I have shown a spider consisting of four arms d secured to the axle and rotating with it. Each of these arms has pivoted 40 to it a shoe e , the outer face of which is curved to the same curvature with the interior of the flange c , and is preferably shod with leather or other suitable substance to produce 45 the proper frictional contact. These shoes have springs f which tend to draw them inwardly when not forced out into contact with the flanges c .

g is a cone sliding upon a feather upon the 50 axle, and actuated by a clutch lever h which is connected with the lever i projecting downward from the shaft j . This shaft extends horizontally along the floor of the car and has handles k at each end so that there being one 55 of these shafts with its handles for the clutch mechanisms of each axle, it will be manifest that the car may be reversed to drive in either direction by the operator whether he be at one end of the car or the other.

60 l are levers fulcrumed to the hub or sleeve within the flanges c as shown at m . The outer ends of these levers rest upon the cones g , and it will be manifest that when the cones are forced toward the levers, the outer ends 65 of the latter will be separated riding upon the surface of the cones, and when the cones are drawn away they will again be depressed

toward the center. These levers are connected with the shoes e by means of rods m' which are screw-threaded at their meeting 70 ends with right and left threads which fit into an intermediate nut o by which the length of these rods is adjusted. The inner end of the inner rod m' is forked so as to fit astride the lever l to which it is pivoted, and it will be 75 manifest that when the lever l is forced outward by the action of the cone g , it will force the outer end of the shoe e into contact with the inner periphery of the flange c . As this takes place simultaneously with each of the 80 four shoes e the frictional contact is sufficient so that the motion of the sprocket wheel S or S' is transmitted to the corresponding spiders d , and through them to the axle to which their hub is keyed. The cone g has a 85 short cylindrical continuation beyond its highest part so that when the points of the levers l have been forced up on this cylindrical portion, they will rest there without any tendency to slide back, and, consequently, there 90 will be no strain or tendency of the levers to slide down the cone as would be the case if the ends remained resting upon the conical portion. By this construction I have greatly simplified the mechanism, making it easy to 95 reverse the car or to stop it while the engine still continues the motion, and the speed of the car may be regulated without the use of intermediate speed mechanism by simply driving the engine faster or slower.

As shown in Fig. 1 ordinary cone frictional devices are illustrated and the relative positions of the gears and driving wheels are changed, but the operation is essentially the same.

Although sprocket wheels and chains have been described to transmit motion between the more distant shafts, it will be manifest that belts may also be used.

Having thus described my invention, what 110 I claim as new, and desire to secure by Letters Patent, is—

1. A car having mounted upon it horizontal gas engines, a single crank shaft to which the oppositely placed engines are coupled, a 115 sprocket wheel fixed upon said crank shaft, a second sprocket wheel fixed upon one of the car axles and a chain extending between the two, a gear wheel fixed upon the crank shaft, a second gear wheel mounted upon a shaft or 120 stud, and engaging with the first gear wheel, a sprocket wheel mounted to rotate with the second gear wheel, a sprocket wheel upon the other car axle and a chain extending between 125 it and the supplemental sprocket wheel, and independent clutch mechanisms whereby reverse motions of the car may be obtained without reversing the engine, substantially as herein described.

2. In a car motor, an engine bed having 130 cast with each end a circular head and a shelf to which the engine cylinders are bolted said bed having the offsets or curves at opposite sides and the axis of the cylinders standing in

different vertical planes upon said bed, a shaft journalized across the center of said bed between the cylinders and having cranks in line with the cylinders, and rods connecting the 5 cranks with the cylinders, substantially as herein described.

3. In a car motor, the irregularly shaped engine bed having cylinders mounted at opposite ends, a transverse crank shaft journalized 10 across the center, to the cranks of which the connecting rods of the two engines are coupled, a sprocket wheel mounted upon the engine shaft, a second sprocket wheel mounted in line therewith upon one of the car axles, and 15 an intermediate driving chain, a supplemental sprocket wheel mounted upon an independent shaft, and a chain extending therefrom to a sprocket wheel upon the other car axle, a gear mounted upon the engine shaft, 20 and a second gear with which it meshes mounted upon the shaft of the supplemental sprocket wheel whereby the latter is driven in the reverse direction from the one upon the engine shaft, and clutch mechanisms whereby either 25 of the sprocket wheels may be connected with its axle, and the car driven in either direction, substantially as herein described.

4. In a car motor, horizontal gas engines mounted upon an engine bed and coupled to 30 a common crank shaft, sprocket wheels and intermediate gears whereby the motions of the engine in one direction may be applied to a sprocket wheel upon one car axle to drive in one direction and to the other car axle to 35 drive in the opposite direction, friction clutches and levers whereby said clutches are actuated so that either axle may be driven by its connection from the engine, or both may be thrown out of gear therewith without stopping 40 the engine, substantially as herein described.

5. In a car motor, a pair of gas engines acting

upon a single crank shaft, sprocket wheels turning loosely upon the car axles and driven in opposite directions by chains from sprocket wheels driven by the engine shaft, a flanged 45 disk connected with the loosely running sleeves of the sprockets upon the car axles, frictional shoes carried by and rotating with the car axles, and a mechanism whereby said shoes are forced into contact with the frictional flanges so that motion from the sprocket 50 wheels is transmitted to the car axles, substantially as herein described.

6. The disks having cylindrical flanges with frictional interior surfaces, said disks turning 55 loosely upon the car axle and having motion transmitted to them by sprocket wheels and chains from the engine shaft, hubs or spiders fixed to the car axle having frictional shoes e fulcrumed to them, and springs by which said 60 shoes are normally kept out of contact with the friction flanges, levers having one end fulcrumed within the flanges and the opposite ends resting upon the surface of a cone movable along the axle, rods hinged to the movable ends of the frictional shoes and to said levers, so as to move the shoes outwardly when the levers are moved, clutch levers by which the sliding cone is moved along the axle 65 whereby the outer ends of the levers which 70 rest upon the cone are moved outward when the cone is forced between them, and allowed to move inwardly to release the frictional shoes when the cone is moved away from them, substantially as herein described. 75

In witness whereof I have hereunto set my hand.

DANIEL BEST.
